MEANS FOR SEALING FOIL WRAPPERS

Eugene A. Jareckie, Madison, N. J., assignor to
 Celluloid Corporation, a corporation of New
 Jersey

Application February 7, 1931, Serial No. 514,179

4 Claims. (Cl. 93—2)

The present invention relates to the art of enclosing articles in wrappers of transparent foils or papers made from cellulose derivatives and relates more particularly to improved means for sealing such foils or papers after the articles have been enclosed thereby.

An object of the present invention is to provide an improved means for sealing by the application of heat and pressure a package wrapped 10 in thermoplastic material.

Other objects and advantages of this invention, together with certain details of construction and combinations of parts will be described in the specification and pointed out in the appended 15 claims.

Transparent foil or paper made of reconstituted cellulose is used to a very large extent in wrapping articles of all kinds. Examples of such articles are confectionery, foodstuffs such as bread, 20 cakes, crackers or meats, cigars, garments such as dresses, underwear, shirts, neckties, etc., etc. In the use of such foil, the foil is wrapped around the article or the article is slipped into envelopes made of the foil and then the loose ends of the 25 foil or the flaps of the envelopes are sealed by the application of a cement, glue or other adhesive. The use of such adhesive is objectionable as it involves a separate operation, introduces a foreign material, often of unpleasant odor, which 30 may decompose or disintegrate on standing and the seal is generally not complete along the whole of its line.

To avoid the use of an adhesive for sealing packages, it has been proposed to employ foils made 35 from organic derivatives of cellulose, which are characteristically thermoplastic instead of foils of reconstituted cellulose which have not the property of thermoplasticity. Because of the thermoplastic character of the organic derivative of cellulose foils, a permanent and continuous seal may 40 be formed on the package by fusion caused by the application of heat and pressure and without the use of any adhesive.

The thin sheets, foils or papers, which it is 45 proposed to use, may contain any suitable organic derivative of cellulose such as organic esters of cellulose and cellulose ethers. Examples of such organic esters of cellulose are cellulose acetate, cellulose formate, cellulose propionate and cellulose butyrate, while examples of cellulose ethers are methyl cellulose, ethyl cellulose and benzyl cellulose. The foils may contain, 50 besides the cellulose acetate or other organic derivative of cellulose, suitable plasticizers such as triacetin, dimethyl phthalate, diethyl phthalate,

dibutyl phthalate, diethyl tartrate, dibutyl tartrate, etc. and any other desired materials such as pigments and effect materials.

The thin sheets or foils containing cellulose acetate are preferably rendered more impervious by coating them with a solution containing cellulose nitrate of either high or low viscosity characteristics. The solution of cellulose nitrate is dissolved in a suitable solvent or solvent mixture which has no appreciable solvent action on the 10 cellulose acetate contained in the surface to be coated, and this solution of cellulose nitrate preferably also contains fire retardants such as tricresyl phosphate or triphenyl phosphate and also water-resistant products such as resins and waxes. 15

I found that the application of heat over the entire width of the lap of the wrapper distorted the foil near the lap and also gave the lap an undesirable cloudy appearance. Furthermore when the pressure was applied over a small area, 20 a groove or dent was left in the article being wrapped. Therefore, in accordance with my invention, I apply pressure over a relatively wide area of the package being wrapped and heat along a narrow area with very satisfactory results. 25

Any suitable organic derivative of cellulose may be employed as a wrapper. An example of a foil found satisfactory for use as a wrapper was made as follows:

	Parts 30
Cellulose acetate.....	100
Diethyl phthalate.....	15
Tricresyl phosphate.....	15

Any suitable form of apparatus may be employed in carrying out my invention. However, I prefer to use a device comprising a supporting member on or into which the wrapped article is placed and a pressure member applied to be mounted on the spindles of a suitable press, the 35 pressure member carrying a sealing member. The sealing member consists preferably of a strip of $\frac{1}{8}$ " brass or copper which is insulated by fibre or other heat insulating material. The pressure member conforms substantially to the shape of 40 the package being sealed and the sealing element to the contour of the lap. The sealing element may be heated by any suitable means such as an electric heating element.

For further illustration of this invention reference is had to the accompanying drawing wherein

Figure 1 is a side elevational view, partly in section of my invention as applied to the sealing of a cigar wrapper;

Figure 2 is a bottom plan view of the pressure member showing the sealing element imbedded therein;

5 Figure 3 is a cross-sectional view taken on line 3—3 in Figure 2;

Figure 4 is a cross-sectional view of the wrapped cigar;

10 Figure 5 is a view, partly in section, of a modification of my invention, showing it as applied to the sealing of the flap of an envelope in which a powder-puff has been placed; and

Figure 6 is a detail view of a pressure member and a sealing element imbedded therein.

15 Like characters of reference indicate corresponding parts throughout the several views.

Referring to Figs. 1 to 4 of the drawing there is shown an embodiment of my invention which is adapted to be mounted as an attachment on a cigar wrapping machine in which transparent 20 foils or papers are used as wrappers, suitable mechanism being provided on said wrapping machine on which the attachment may be mounted. The attachment comprises a supporting member 7 for receiving a foil wrapped cigar 8 fed thereto 25 by any suitable means and a pressure and sealing member generally indicated by the reference numeral 9 adapted to seal the lap indicated at A in Figure 4. The latter member consists of a copper bar 10 to which is rigidly attached a 30 fibre insulating member 11 which should preferably be slightly wider than the cigar being sealed. The copper bar and the insulating member are slotted at 12 and 13, respectively, to receive a brass or copper fin 14, the construction and arrangement being such that the lower end contacting portion of the fin is in the plane of the working surface of the insulating member. The working surfaces of said insulating member and fin are shaped to the longitudinal profile of the 35 cigar in order to produce a perfect seal from tip to tip thereof.

The copper bar 10 is connected to a suitable heating element (not shown) and is adapted to transfer heat to the fin in such a manner that 40 the heat will be evenly distributed thereover. It is to be understood that the temperature and pressure requirements will vary depending on the formula used in making the thermoplastic foil. If the foil is made with sufficient plasticizer, 45 especially if the latter is of the solvent type, such as dimethyl phthalate or triacetin, comparatively low temperatures, say 250° to 350° F., will suffice. In the case of a limited amount of plasticizer being used, or where the plasticizers are 50 not of the solvent type, such as aromatic phosphates, then more heat and pressure will be found necessary. However, in the foil of the formula given above, I have found that the best 55 temperature to use is from 250° F. to 350° F. and the pressure which gave the best results was from 100 pounds to 500 pounds per square inch. The 60 time of pressing may vary from half a second to one minute.

In Figures 5 and 6, I have shown my invention as applied to the sealing of the flap of an envelope into which has been inserted a powder-puff. The supporting member 15 and the pressure and sealing member 16 may be attached to 5 the spindles of a suitable press. The fin 17 and insulating element 18 are curved to conform to the shape of the flap 19 of the envelope 21 and may be of any length desired.

It will be apparent from the foregoing description that I have produced a simple, inexpensive and highly efficient device for sealing a package wrapped in a thermoplastic material. However, it is to be understood that the foregoing description is given merely by way of illustration and 15 that many variations may be made therein without departing from the spirit of the invention.

Having described my invention, what I desire to secure by Letters Patent is:

1. In apparatus for sealing a package wrapped 20 in thermoplastic material, a pressure member comprising a bar and an insulating member attached thereto and a heated element carried by said pressure member, the working surface of said heated element being relatively narrow in 25 comparison with that of said pressure member and being located in position to apply heat only along a restricted portion of the lap of the wrapper.

2. In apparatus for sealing a package wrapped 30 in thermoplastic material, a pressure member comprising a metallic bar and an insulating member attached thereto and a heated element carried by said pressure member, the working surfaces of said insulating member and said heated 35 element being in the same plane, and the working surface of said heated element being relatively narrow in comparison with that of said pressure member and being located in position to apply heat only along a restricted portion of 40 the lap of the wrapper.

3. In apparatus for sealing a package wrapped 45 in thermoplastic material, a pressure member comprising a metallic bar adapted to be heated and an insulating member attached thereto and a fin carried by said pressure member, said fin being adapted to be heated by said bar and having a working surface which is relatively narrow in 50 comparison with that of said pressure member.

4. In apparatus for sealing a package wrapped 55 in thermoplastic material, a pressure member having a working surface of substantially the same width as the package being sealed and a sealing member, comprising a heated metallic fin carried by said pressure member, said fin having a working surface which is relatively narrow in 60 comparison with that of said pressure member and which is located in position to apply heat only along a restricted portion of the lap of the wrapper.

EUGENE A. JARECKIE.
